(57) **CLAIM**

We claim the ornamental design for a cooking grill, as shown and described.

DESCRIPTION

FIG. 1 is a top, front and right side perspective view of a cooking grill showing our new design;
FIG. 2 is a front elevational view thereof;
FIG. 3 is a rear elevational view thereof;
FIG. 4 is a right side elevational view thereof;
FIG. 5 is a left side elevational view thereof; and,
FIG. 6 is a top plan view thereof.

The broken lines are included for the purpose of illustrating portions of the cooking grill that form no part of the claimed design.
